TYPEWRITING MACHINE

George G. Going, Glenbrook, Stamford, Conn.,
assignor to Remington Typewriter Company,
Ilion, N. Y., a corporation of New York

Application June 24, 1931, Serial No. 546,466

14 Claims. (Cl. 197—27)

My invention relates to typewriting machines and more particularly to the type actions thereof and to the manner of constructing and mounting certain levers in the machine.

5 The main object of my invention, generally stated is to provide a very simple yet efficient construction involving but comparatively few and inexpensive parts that may be made and readily assembled and united at a comparatively small cost, thus aiding in the construction of a 10 very cheap yet efficient typewriting machine.

A further object of my invention is to provide a construction of the character specified in which nearly all of the parts may be made from sheet metal.

15 A still further object of my invention is to produce a comparatively small, simple and compact portable typewriting machine that is light in weight and may be produced at small cost.

20 To the above and other ends which will hereinafter appear, my invention consists in the features of construction, arrangements of parts and combinations of devices set forth in the following specification and particularly pointed out in the 25 appended claims.

25 In the accompanying drawings wherein like reference characters designate corresponding parts in the different views—

Fig. 1 is a vertical, fore and aft, sectional view 30 of the machine.

Fig. 2 is a fragmentary, top plan view with parts in section showing one half of the type actions and some of the associated parts.

35 Fig. 3 is an enlarged, detail, perspective view, with parts broken away, of one of the space key levers mounted in condition for use.

Fig. 4 is a like fragmentary view of the same with the stop projection thereon shown in full lines bent to ineffective position.

40 Fig. 5 is an enlarged, detail, perspective view showing the means for connecting each key lever to its sub-lever.

Fig. 6 is an enlarged, detail, perspective view showing the means for supporting the key lever 45 springs on the side plates of the frame.

Fig. 7 is an enlarged, detail, fragmentary, perspective view of the key lever returning springs, the view showing one of said springs with its key lever mounted thereon.

50 I have only shown so much of the machine as is necessary to arrive at an understanding of my present invention in its embodiment therein. There are features disclosed but not claimed herein that will be claimed in separate applications.

The frame of the machine comprises side plates 1, a front plate 2 and a rear plate 3, all preferably made from sheet metal. The front plate 2 is secured by screws 4 to inturned flanges on the side plates 1, whereas the rear plate 3 is secured by screws 6 in a like manner to inturned flanges 7 on the side plates. The side plates 1 are further united by a casting 8 secured at its ends to the side plates by screws 9 and 10. The casting 8 is the only casting used in the machine and will be hereinafter referred to more in detail. A U-shaped sheet metal frame 11 surrounds the keyboard of the machine and is secured by screws 12 to the side plates 1.

5 A suitable carriage (not shown) is mounted to travel from side to side of the machine and carries a cylindrical platen 13. Carried by the carriage is a sheet metal feed rack 14 with which sheet metal feed dogs 15 and 16 coact to advance the carriage in its step-by-step letter space movement under the propulsion of suitable spring means, not shown. The feed dogs 15 and 16 are carried by a sheet metal dog rocker frame 17 pivoted at 18 and forming part of a universal bar 19.

20 As shown in the present instance a universal bar 19 is actuated by a projection 20 on the heel of each of the sheet metal type bars 21, whereas said universal bar and the frame 17 connected therewith are returned to normal position by a 25 spring 22.

25 The heels of the type bars 21 are received and guided in radially disposed guide slots 22 in a type bar segment 23 formed as a part of the casting 8. The type bars are pivoted on a curved 30 pivot wire 24 disposed in a horizontal plane or at right angles to a plane tangent to the platen at the printing line. The type bars are all moved in converging planes and impact at a common 35 printing center where they cooperate with a 40 type bar center guide 25.

Due to this arrangement of the pivotal centers of the type bars each of said bars is devoid of lateral bends and I am therefore enabled to provide a close arrangement of the type bars in the basket and move each type bar through a comparatively short arc to the printing point. Each type bar is provided at the heel thereof with a rounded crank arm or actuating projection 26 that has a movement in the plane of movement 45 of its type bar and is confined between the side walls of the guide slot 22 within which the companion type bar works, as will be understood from a consideration of Fig. 1. Each projection 26 is received in the opening between the arms of the 50

rear bifurcated end 27 of a companion substantially horizontally disposed, sheet metal, sub-lever 28 of the first order, said bifurcated end being received in the companion slot 22 and guided by 5 the side walls thereof and moving in a plane corresponding to that of the associated type bar. It will be understood, therefore, that by this construction the bifurcated end of each sub-lever and the projection 26 on the associated type bar are 10 held against lateral movement relatively one to the other by the side walls of the companion slot 22, and are thus maintained in cooperative engagement when the parts are assembled.

Each sub-lever 28 is provided with a recess 29 15 in the bottom edge thereof about midway in the length thereof. A curved sheet metal fulcrum bar or plate 30 is received at its upper rounded edge in the recesses 29 in the various sub-levers and constitutes a support and fulcrum therefor. The 20 fulcrum bar is secured at its ends by screws 31 to the casting 8. A separate and distinct curved sheet metal guide comb 32 is arranged above the fulcrum bar 30 and is separately secured at its 25 ends to the casting 8 by screws 33. The slots 34 in the guide comb are closed at the top and open at the bottom and receive and guide the sub-levers at the points of support of the latter on the fulcrum bar.

The forward end of each sub-lever is bent laterally to provide a lug 35 perforated at 36 to detachably receive an upwardly and rearwardly extending engaging finger or projection 37 on the associated key lever 38, provided with a finger key 39. It will be seen that the levers 38 are all arranged and move in parallel planes that extend fore and aft of the machine, whereas the sub-levers 28 extend radially from the wider system of key levers to the narrower system of type bars. Moreover, from a consideration of Fig. 2 it will be 40 seen that the points of engagement between each sub-lever and its type bar and key lever and the fulcrum point for such sub-lever, all lie in the same radial plane, which plane is coincident with the plane of movement of the associated type bar. 45 Due to this arrangement there is no side strain in transmitting movement from any key lever to its type bar and a very light and satisfactory type action is provided consisting of but three parts.

It will be seen, moreover, that although sub-levers 28 of various lengths are provided throughout the system to reach from the type bars to the respective key levers to which said sub-levers are directly connected, and that the points of contact between the parts of each type action in the same 50 plane is maintained, as pointed out above there is provided, nevertheless, a substantially uniform leverage throughout the system due to the approximate maintenance of the same ratio between the two arms of each sub-lever throughout the system. The difference in the points of engagement between the sub-levers 28 and the key levers 38, as shown in Fig. 2, compensates for the difference in the lengths of the key levers, all of which are mounted at their rear ends in a straight line 55 across the machine. This last mentioned feature of the construction further provides for the maintenance of a uniform leverage throughout the system.

The key levers 38 are guided at their forward ends in guide slots 40 in the lower edge of the front plate 2 of the frame, which in effect provides a guide comb for the key levers. The rear end of each key lever is bifurcated at 41 to receive and closely embrace the free forward end of a leaf 60 spring 42 and provide a pinching engagement

therewith under the reaction of the spring. In order to prevent a lateral displacement of each key lever relatively to its spring 42, the forward end of the spring is recessed at 43 to closely embrace both sides of the companion key lever when the parts are assembled, thus providing an interlocking though rigid connection between each key lever and its spring. The reactive force of each spring 42 not only is exerted to maintain a pinching engagement between it and its key lever, but 10 also returns the key lever and the other parts of the type action controlled thereby to normal position, where the key lever is arrested by the top wall 44 (Fig. 3) of the guide slot 40 in which it is received. The springs 42 are preferably formed 15 from a single strip of metal 45 anchored and riveted at 46 to an underlying sheet metal strip 47 and to an overlying supporting plate or cross bar 48. This plate 48 is provided with lugs 49 at each end thereof, said lugs being received in apertures 20 50 in the side plates 1. The ends of the lugs are preferably riveted over at 51 to firmly connect the supporting plate to the frame and further unite the side plates thereof. It will be understood that by this construction each key lever receives its 25 pivotal movement by a flexing of its companion spring 42, as shown in full lines in Fig. 1, and that each key lever is carried and supported by its spring and returned to normal position thereby. This gives a cushioning effect on each type action 30 and constitutes an inexpensive yet flexible and highly efficient means for actuating each type bar and for mounting and assembling the key levers in the machine and returning the parts of each type action to normal position. For example, 35 the resistance offered to the actuation of each key lever by its sub-lever and type bar, reacts in part against the companion spring 42 and softens or cushions the action of the key lever in transmitting motion to the type bar. This effect, of course, is more pronounced at the bottom of the key stroke if the operator should exert a long following stroke on the key, continuing the pressure even after the type bar reaches the printing point. 45

In addition to the foregoing I have provided another novel lever mounting by which certain of the levers employed may be readily introduced and assembled in the machine and may be readily detached when desired. In the present instance these levers constitute means by which the space key is supported and by which motion is transmitted therefrom to the dog rocker frame. It should be understood, however, that the lever construction in question is not restricted to such use but may be employed for transmitting motion to other parts of a typewriting machine such, for example, as a type action. 50 55

The space key 52 is connected to and unites two angular levers, each designated as a whole by the reference numeral 53. These levers are substantially the same in construction and a description of one of them will suffice. Each lever 53 has a forwardly extending arm 54 connected at its forward end by spot welding or other means 60 to the space key 52 and has an upright arm 55 in the rear of the front plate 2 of the frame. The arm 55 carries a forwardly extending, substantially T-shaped, arm or projection 56 adapted to be received and guided for pivotal movement in 65 a slot or aperture 57, and fulcrum on the bottom wall 58 thereof when the lever is mounted in place. When the lever is in place the bottom wall 58 of the slot 57 is seated in a recess 59 in the lever. At this time the lower end 60 of the 70 75

head of the T-shaped projection 56 extends down in front of the body portion of the plate 2, whereas the upper end 61 of the cross head is received in the slot 57 and by coacting with the upper wall of the slot prevents an upward movement of the lever off its fulcrum 58 without, however, interfering with a limited pivotal movement of the lever.

The limit of pivotal movement of the lever 53 in one direction is determined by the forward edge of the upright arm 55 thereof abutting the front plate 2 of the frame. The limit of pivotal movement of the lever in the opposite direction is determined by a bendable forwardly extending stop or projection 62 on the lever coacting with the front plate 2 when said stop is bent to effective position shown in Fig. 3 and in dotted lines in Fig. 4. So long as the stop 62 remains in such effective position the lever 53 cannot be detached from its support 2. When, however, the stop 62 is bent to some such ineffective position as that indicated in full lines in Fig. 4, the upper end of the lever 53 may be moved further forward to clear the upper end 61 of the head from the upper wall of the slot 57. The lever may then be lifted and the lower end thereof swung rearwardly and the T-shaped head as a whole may be withdrawn from the slot 57 and the lever detached. The fact that in the present instance both levers 53 are united by the space bar 52 does not interfere with both levers being mounted in place or demounted together in the manner indicated above.

When assembling the parts of the construction just described, a coiled expansion spring 63 is placed on each projection or stop 62 while it is in the ineffective, full line, Fig. 4 position. Each stop with a spring on it is then bent to the Fig. 3 position bringing one end of the associated spring against the rear face of the front plate 2, whereas the opposite end of the spring bears against the upright arm which supports the stop 62. Each spring 63 will then function as a return spring for its lever 53.

One of the levers 53 in the present instance is pierced at 64 to receive a bent end of a push rod 65 received in the present instance at its rear bent end in a slot 66 of a depending arm 67 on the dog rocker frame 17.

A depression of the space key 52 transmits a rearward movement to the push rod 65 thus actuating the dog rocker frame to control the step-by-step feed of the carriage.

While one of the main objects of my invention is to produce a machine that may be manufactured at small cost, the construction is such, nevertheless, that a simple, extremely light, rapid and highly effective type action, or system of type actions, is produced that may be incorporated in various styles of typewriting machines irrespective of the cost of the machine as a whole to manufacture.

Various changes may be made in the construction, and parts thereof may be employed without others, without departing from my invention as it is defined in the accompanying claims.

What I claim as new and desire to secure by Letters Patent is:

1. A type action comprising a key lever, a leaf spring on which said key lever is mounted and by which it is carried and returned to normal position, means for anchoring and holding fast said leaf spring at one end, and means for rigidly though readily detachably connecting the

other end of the spring to said key lever, the construction and arrangement of said connecting means being such that a pinching engagement is maintained between the key lever and spring by the reaction of the spring and that tends to hold the key lever connected to the spring.

2. A type action comprising a key lever, a leaf spring on which said key lever is mounted and by which it is carried and returned to normal position, means for anchoring said leaf spring at one end, and means for rigidly though readily detachably connecting the other end of the spring to said key lever, the construction and arrangement of said connecting means being such that a pinching engagement is maintained between the key lever and spring by the reaction of the spring and a positive interlocking against relative sidewise displacement between the spring and key lever is provided.

3. The combination of a lever having a substantially T-shaped projection thereon by which the lever is supported for pivotal movement, a supporting plate having a slot in which said T-shaped projection is received and on the bottom wall of which the lever fulcrums, and a separate bendable projection on said lever which when bent to effective position prevents a demounting of said lever from said supporting plate.

4. The combination of a lever having a substantially T-shaped projection thereon by which the lever is supported for pivotal movement, a supporting plate having a slot in which said T-shaped projection is received and on the bottom wall of which the lever fulcrums, a separate bendable projection on said lever which when bent to effective position prevents a demounting of said lever from said supporting plate, and a returning spring for said lever on said bendable projection.

5. The combination of a lever having a substantially T-shaped projection thereon by which the lever is supported for pivotal movement, a supporting plate having a slot in which said T-shaped projection is received and on the bottom wall of which the lever fulcrums, a separate bendable projection on said lever which when bent to effective position prevents a demounting of said lever from said supporting plate, and a coiled expansion spring that surrounds said bendable projection and which spring when the bendable projection is in effective position bears at one end against the lever and at its other end against said supporting plate and operates as a return spring to return the lever to normal position.

6. The combination of a lever having a substantially T-shaped projection thereon by which the lever is supported for pivotal movement, a supporting plate having a slot in which said T-shaped projection is received and on the bottom wall of which the lever fulcrums, and a separate bendable projection on said lever which in its effective position limits the movement of the lever in one direction and prevents the detachment of the lever from said supporting plate, the movement of the lever in the opposite direction being limited by the body portion thereof coacting with the supporting plate.

7. The combination of a series of key levers arranged in parallelism throughout the lengths thereof, an engaging projection on each of said key levers extending therefrom intermediate its ends, a series of upwardly and rearwardly moving front strike type bars narrower in width than said series of key levers, and a series of substan-

tially horizontally disposed sub-levers that extend inwardly from the key levers to the type bars and are directly connected to the latter, each of said sub-levers having an aperture therein through which the said engaging projection on the associated key lever extends.

8. The combination of a series of key levers arranged in parallelism throughout the lengths thereof, an upwardly and rearwardly disposed engaging projection on each of said key levers intermediate the ends thereof, a series of upwardly and rearwardly moving type bars narrower in width than said series of key levers, and a series of substantially horizontally disposed sub-levers that extend inwardly from the key levers to the type bars and each of which is bifurcated at its rear end to receive a projection on the associated type bar, the bifurcated end portion of each sub-lever and its associated type bar moving in the same plane, the forward end of each sub-lever being apertured to receive the upwardly and rearwardly extending engaging projection on the companion key lever.

9. The combination of a radially disposed type bar, a key lever that extends fore and aft of the machine, an intermediate radially and horizontally disposed sub-lever of the first order readily detachably connected directly with said key lever and type bar, said sub-lever having a recess therein intermediate its ends and at the point where it is fulcrumed, and means for mounting said sub-lever for ready assembly and demounting comprising a curved sheet metal fulcrum bar or member one edge of which is received within said recess in the sub-lever and provides a fulcrum therefor, and an independently detachable sheet metal curved guide comb open at the bottom and closed at the top and arranged above and coincident with said curved fulcrum bar and in a guide slot in which guide comb the radially disposed sub-lever is received and works.

10. The combination of a lever, and means for demountably mounting said lever on its fulcrum comprising a fixed plate on which said lever is fulcrumed and supported, and a bendable projection on said lever which when bent to its effective position prevents the detachment of the lever from said fixed plate and which when bent to ineffective position affords a detachment of the lever from said plate.

11. The combination of key levers mounted to move in parallel planes that extend fore and aft of the machine, a series of pivoted front strike type bars mounted to move in radial converging planes and each having an actuating projection thereon, the series of type bars being narrower in width than the series of key levers, radially and horizontally disposed sub-levers of the first order intermediate said type bars and key levers, the fulcrum point of each sub-lever and the points of connection of each sub-lever with its associated type bar and key lever being in the

plane of movement of the companion type bar, each of said key levers having an engaging finger or projection intermediate the ends thereof and each of the sub-levers being apertured at one end to receive the engaging projection on the associated key lever and each sub-lever being bifurcated at the other end to receive a projection on the associated type bar, whereby the key levers, type bars and sub-levers may be readily assembled and connected.

12. In a front strike typewriting machine the combination of key levers mounted to move throughout the lengths thereof in parallel planes that extend fore and aft of the machine, a system of front strike type bars pivoted in a horizontal plane to move upwardly and rearwardly in radial converging planes, the system of type bars being narrower in width than the system of key levers, radially and substantially horizontally disposed sub-levers intermediate said type bars and key levers and directly and detachably connected therewith, the fulcrum point of each sub-lever and the points of connection of each sub-lever with its associated key lever and type bar being in the same plane which is substantially coincident with the plane of movement of the companion type bar, and means for demountably supporting said sub-levers on the fulcrum therefor, said last mentioned means comprising a comb plate that overlies the fulcrum and prevents a removal of the sub-levers therefrom.

13. A type action comprising a key lever, a leaf spring on which said key lever is mounted and by which it is carried and returned to normal position, means for anchoring and holding fast said leaf spring at one end, and means for rigidly though readily detachably connecting the other end of the spring to said key lever, said connecting means comprising a bifurcated portion at the rear end of the key lever to receive and closely embrace the free end of the spring and provide a pinching engagement therewith under the reaction of the spring.

14. A type action comprising a key lever, a leaf spring on which said key lever is mounted and by which it is carried and returned to normal position, means for anchoring and holding fast said leaf spring at one end, and means for rigidly though readily detachably connecting the other end of the spring to said key lever, said connecting means comprising a bifurcated portion at the rear end of the key lever to receive and closely embrace the free end of the spring and provide a pinching engagement therewith under the reaction of the spring, the free end of the spring being recessed to closely embrace both sides of the key lever and thus provide an interlocking engagement between the lever and its spring that prevents a lateral displacement of the lever relatively to its spring.

GEORGE G. GOING.
